UNITED STATES PATENT OFFICE.

HORACE H. TAYLOR, OF FRESNO, ASSIGNOR OF ONE-HALF TO ROBERT POLLARD, OF SAN LUIS OBISPO, CALIFORNIA.

ORE-SEPARATOR.

SPECIFICATION forming part of Letters Patent No. 460,732, dated October 6, 1891.

Application filed April 7, 1891. Serial No. 387,943. (No model.)

To all whom it may concern:

Be it known that I, HORACE H. TAYLOR, a citizen of the United States, residing at Fresno, in the county of Fresno and State of California, have invented a new and useful Gold-Separator, of which the following is a specification.

This invention relates to separators of that class known as "dry separators," the object 10 being to provide a cheap, simple, easily-operated machine adapted to effectually separate the gold from the sand without the use of water, mercury, or other agent, and simply by blasts of air.

15 Other objects and advantages of the invention will appear in the following description, and the novel features thereof will be particularly pointed out in the claims.

Referring to the drawings, Figure 1 is a perspective of a gold-separator constructed in accordance with my invention. Fig. 2 is a vertical longitudinal section on the line 2 2 of Fig. 3. Fig. 3 is a rear elevation. Fig. 4 is a detail in perspective of the intermittent reciprocating scraper and the mechanism for operating the same. Fig. 5 is a detail in perspective of the rotary cut-off.

Like numerals of reference indicate like parts in all the figures of the drawings.

30 In practicing my invention I employ the opposite side frames or standards 1, and in the opposite longitudinal sides of same form bearings 2, which receive the laterally-disposed opposite trunnions 3 of the separator-casing 35 4. The separator-casing 4 has supported between its opposite side walls the ore-receiving hopper 5, having an inclined bottom terminating in reduced neck or spout 6. Below and in front of the hopper the side walls of 40 the casing are extended, as at 7, and each is provided upon its inner surface with a longitudinal cleat 8, below which some distance is located the upper member 9 of a pair of bellows 10, said members being hinged together 45 at their front ends, as at 11. The upper member of the bellows is simply an open frame, and seated upon the same is the riffle 12, having the usual riffle-bars 13 and the reticulated or screen bottom 15. The cleat 8 does not extend 50 parallel with the riffle-frame, and, being located slightly above the same, forms oppo-

site wedge-shaped spaces at the inner sides of the casing, and into said spaces are forced wedge-shaped keys 14, which terminate at their front ends in handles 16, by which they may be inserted and withdrawn, and thus the riffle-frame secured in position or removed, as desired. The lower section or member 17 of the bellows is provided with a series of air-inlet ports 18, each covered by a clack-valve 19. These ports and valves may be increased or diminished in accordance with the force of the blast deemed necessary.

A series of hangers 20 depends from the upper member 9 of the bellows into the same, 65 and supported thereby is a pan 21, located under the riffle and designed to catch the small particles of gold should any escape from the riffle by passing through its reticulated bottom.

At the rear side of the hopper 5 is located a pair of bearing-brackets 23, in which is mounted a transverse shaft 24, having a central crank 25. At one end of the shaft is mounted a fly-wheel 26, and to one side of the fly-wheel a sprocket-wheel 27. In vertically-opposite brackets 28, extending rearwardly from the hopper and the upper member 9 of the bellows, there is mounted for reciprocation a vertical shaft 29, connected by a link 30 with an arm 31, extending rearwardly from the lower member of the bellows. Between its ends the shaft 29 is provided with a horizontally-disposed yoke 32, which is coincident with the crank 25 of the shaft 24, and by the revolutions of the crank within the yoke the latter, together with its vertical shaft, is raised and lowered. Below the yoke the shaft 29 is provided with a transverse pin 33. Upon the under side of the inclined bottom of the hopper is a pair of bearing-brackets 36, which are located slightly in rear of the reduced discharge 6 of the hopper, and in said bearing-brackets a shaft 37 is located, upon which near the brackets is mounted a pair of rock-arms 38 and a central rock-arm 39, disposed at a right angle to the arm 38 and having a bifurcated end 40, which embraces the shaft 29 and loosely the pin 33 of said shaft. The depending arms 38 terminate at their lower ends in eyes 41, which loosely receive the transverse bar 42, formed at the rear end of

a reciprocating rod 43, having a head 44 at its front end, to which is hinged, as at 45, a scraping-blade 46, said rod being mounted for reciprocation in a transverse wall 47 in rear of the reduced opening 6 of the hopper, and directly above the upper member 9 of the bellows, which member serves also as the bottom of the casing, in contact with which the blade normally is.

10 A shaft 48 is journaled in the opposite walls of the casing, and carries outside of the casing a sprocket-wheel 49, and within said casing a rotatable intermittent cut-off 50, consisting of a central hub 51 and radiating L-shaped blades 52, the heads of which are rounded, as shown, and adapted to successively close the discharge-spout of the hopper.

15 In brackets 53, located at the front and secured to the hopper, are formed bearings 54, and in the same a rotatable shaft 55 is journaled, the bearings of said shaft being made adjustable by a threaded rod 56 and its nut 57, the rod engaging at its inner end the upturned perforated end 58 of the boxing, which latter is movable upon the bracket. Upon one end of the shaft 55 a crank 59 is mounted, and upon the other end a sprocket 60. The sprockets 60, 49, and 27 are all connected by a sprocket-chain 61, through which motion is 20 conveyed from the power-shaft 55, operated by crank or otherwise, to the several mechanisms heretofore described.

25 This being the construction, the operation is as follows: The sand and gold are placed in the hopper 5 and the machine started, and the motion conveyed to the shaft 24, through the means heretofore described, causes a vertical reciprocation of the bellows-operating shaft 29, and consequently blasts of air are 30 forced in quick successions from the bellows up through the reticulated bottom of the rifle-frame. The vertical reciprocations of the shaft 29 are also communicated to the rock-shaft 37 and its arms 39 and 41, so that 35 the latter act to reciprocate the rod 42 and the scraping head or blade 46. As the blade passes to the front its lower edge is in contact with the bottom of the casing, and thus any matter in its path is carefully pushed into the rifle-frame. In returning, however, by reason 40 of the blade being hinged, it yields or swings, so as to pass over any obstruction which may have fallen from the hopper in rear of the scraper-blade when the latter was in its advanced position. The rotary motion imparted 45 to the sprocket 49 rotates the rotary cut-off 50, bringing the heads 52 of the radiating arms or blades thereof successively under and thus closing the discharge-opening of the hopper; 50 and in this manner the contents of the hopper—that is, the mixture of sand and gold—are discharged in uniform quantity and at intervals, in front of the scraper and onto the rifle-frame. The blasts of air accomplish the 55 remainder of the operation, serving as they do to blow the lighter constituents of the mass—that is, the sand—up through the open

top of the casing, and the riffle-bars serving to catch the gold dust or nuggets, which are the heavier and readily settle. Such particles 70 of gold as are sufficiently minute to escape through the meshes of the rifle-frame are caught by the pan and thus collected, to be subsequently removed when desired.

The numerous advantages arising from 75 what is usually termed "dry separation" are well recognized and require no definite mention. At the same time it might be observed that the machine above described possesses the additional advantages of simplicity, strength, 80 durability, and ease of operation, and that the numerous parts composing the apparatus may be readily constructed, assembled, and duplicated when impaired.

Having described my invention, what I 85 claim is—

1. In a separator, the combination, with a hopper, a casing supporting the same, a rifle-frame located below and sliding in front of the discharge of the hopper, and a reciprocating 90 scraping-blade located under the hopper in rear of the riddle-frame, of means for reciprocating the blade, substantially as specified.

2. In a separator of the class described, the combination, with the casing, the hopper terminating at its lower end in a discharge, and a rifle-frame located below the bottom of the casing and in advance of the discharge, of a reciprocating bar terminating in a head and having a hinged scraping-blade, a horizontal 100 shaft, a pair of rock-arms terminating in eyes depending from the shaft and engaging the reciprocating bar, a bifurcated rock-arm extending from said shaft at a right angle to the first-mentioned arms, a vertically-reciprocating shaft having a transverse pin, means for operating the same, a cut-off located under the hopper, and means for intermittently operating the same, substantially as specified.

3. In a separator of the class described, the combination, with the casing, the hopper terminating in a discharge, the rifle-frame located below and in advance of the discharge, the bellows below the frame, the rotary cut-off having the L-shaped blades, the shaft for 110 the same, and the sprocket on the shaft, the reciprocating bar 43, having the hinged blade 45 and the cross-bar 42, the brackets upon the under side of the hopper, the horizontal and depending arms, the latter engaging the cross-bar 42 and the former bifurcated, the shaft 24, mounted in bearings 23, having the crank 25, the sprocket 27, and the fly-wheel 26, of the bearings 28, the vertical shaft 29, mounted therein, having the yoke 32 and connected with the bellows by the link 30, the brackets 53, the adjustable shaft 55, the sprocket 60, the crank for operating the shaft, and the sprocket-chain 61, passing around the sprockets 60, 49, and 27, substantially as 120 125 130 specified.

4. In a separator, the combination, with a hopper, a casing supporting the same, a rifle-frame located below and sliding in front of the

discharge of the hopper, and a reciprocating scraping-blade located under the hopper in rear of the riddle-frame, of means for reciprocating the blade, said blade being hinged at the top, so as to yield or swing backward when in its receding movement, substantially as specified.

In testimony that I claim the foregoing as my own I have hereto affixed my signature in presence of two witnesses.

HORACE H. TAYLOR.
